UNITED STATES PATENT OFFICE.

THOMAS MADDOCK, OF NEW YORK, N. Y.

DESIGN FOR TABLE-WARE.

SPECIFICATION forming part of Design No. 11,828, dated June 22, 1880.

Application filed May 20, 1880. Term of patent 7 years.

To all whom it may concern:

Be it known that I, THOMAS MADDOCK, of New York city, in the county and State of New York, have invented a new and Improved 5 Design for Handles, &c., of China, Earthen, and Metal Table-Ware, Jugs, Toilet Articles, and the like, of which the following is a specification.

My design is to be known as the "chain" 10 shape, and is fully represented in the drawing.

The accompanying drawing is a perspective view.

My design includes a solid base, which, rising 15 up with curved ends, supports a bar. Ornamental chain-work is laid over the bar on both sides, following the line of the curved ends, and forming a crescent-shaped space in

the center, which may be made open, as shown, or left solid. At each end of the handle, on 20 the cover or dish, is raised ornamental chain-work, connecting with the handle.

In the drawing, *a* designates the solid base of the handles, with curved ends *b b*. *c* designates the bar, and *d* the ornamental chain-work. *e* designates the "crescent" formed by the curved ends *b b* and chain-work *d*.

What I claim as my invention, and desire to secure by Letters Patent, is—

The design for china, earthenware, and 30 metal table-ware, &c., substantially as herein shown and specified.

THOMAS MADDOCK.
